Primary Examiner — Ian Simmons*Assistant Examiner* — Keith Frank(74) *Attorney, Agent, or Firm* — Mark M. Friedman(57) **CLAIM**

The ornamental design for a candle holder, as shown and described.

DESCRIPTION

FIG. 1 is a perspective view of a candle holder showing my new design; and,

FIG. 2 is a front elevation view thereof, the rear, left and right elevations being identical.

The rear view is a mirror image of the front side.

The left and right sides are identical with the front side.
